(57) **CLAIM**

The ornamental design for a bottle cap, as shown and described.

DESCRIPTION

FIG. 1 is a front perspective view of a bottle cap, showing our new design.

FIG. 2 is a front elevational view of the bottle cap of FIG. 1.

FIG. 3 is a rear elevational view of the bottle cap of FIG. 1.

FIG. 4 is a left side elevational view of the bottle cap of FIG. 1.

FIG. 5 is a right side elevational view of the bottle cap of FIG. 1.

FIG. 6 is a top plan view of the bottle cap of FIG. 1; and, FIG. 7 is a bottom plan view of the bottle cap of FIG. 1. Broken lines in the figures show features that form no part of the claimed design.
